UNITED STATES PATENT OFFICE.

DANIEL S. WAUGH, OF DENVER, COLORADO, ASSIGNOR TO THE DENVER ROCK DRILL MANUFACTURING COMPANY, OF DENVER, COLORADO, A CORPORATION OF DELAWARE.

ROTATING MEANS FOR ROCK-DRILLS.

1,084,183.

Specification of Letters Patent.

Patented Jan. 13, 1914.

Application filed July 7, 1913. Serial No. 777,692.

To all whom it may concern:

Be it known that I, DANIEL S. WAUGH, a citizen of the United States, residing at Denver, in the county of Denver and State of Colorado, have invented new and useful Improvements in Rotating Means for Rock-Drills, of which the following is a specification.

The present invention relates to means for automatically effecting the rotation of a chuck from the piston of a motor actuated by fluid under pressure, and the primary object is to provide an exceedingly simple, and yet thoroughly practical mechanism for this purpose that is made up of few parts, and is not only comparatively inexpensive to manufacture, but is effective in operation.

An embodiment of the invention is illustrated in the accompanying drawings, 20 wherein:—

Figure 1 is a longitudinal sectional view through a portion of a motor equipped with the rotating means. Figs. 2 and 3 are respectively cross sectional views on the lines 25 2—2 and 3—3 of Fig. 1. Fig. 4 is a detail perspective view of the piston and tappet. Fig. 5 is a similar view of the feather element or ring. Fig. 6 is a detail sectional view illustrating one of the spring plungers 30 for insuring proper coaction between the ratchet or clutch elements. Fig. 7 is a detail perspective view of the clutch ring and the rear end of the chuck.

Similar reference numerals designate corresponding parts in all the figures of the drawings.

In the embodiment illustrated, a cylinder member 8 is employed having a front head 9 and containing a reciprocating piston 10 of the hammer type. The piston is reciprocated by air or other fluid under pressure, which may be controlled and distributed by any well known means. Secured to the cylinder in advance of the head 9, is a feather element or ring 11, on the front end of which is mounted a chuck barrel or casing 12. The piston 10 is of the hammer type, and has a reduced stem 13 passing through the head 9, the ring 11, and into the barrel or casing 12.

50 This stem is provided with one or more longitudinal grooves 14, and one or more spiral grooves 15, two of each set being shown, though the number may be varied.

The ring 11, it will be understood, is fixed 55 with relation to the cylinder 8, and is pro-

vided with inwardly extending feathers 16 that are engaged in the spiral grooves 15. It will thus be evident that the piston 10 upon its reciprocation is given an oscillatory movement on its longitudinal axis.

60 A clutch member or ring 17 surrounds the stem 13 of the piston, and is provided with rearward extensions 18 that are located within the ring 11 and have inwardly extending feathers 19 engaged in the longitudinal 65 grooves 14 of the stem 13. This clutch member 17, while it has a slight longitudinal play, is thus slidably connected to the piston 10 and is caused to oscillate therewith.

Fixed against longitudinal movement in 70 the barrel or casing 12, is a chuck in the form of a sleeve 20 that is freely rotatable, and is provided with suitable means in the form of a bushing 21 for receiving the inner 75 end of a tool 22, the tool and the socket receiving the same, preferably being angular in cross section, so that the tool must rotate with the chuck while it has free longitudinal play therein. Arranged within this chuck, is a suitable tappet 23 that is struck by the 80 front end of the piston stem 13 and transmits the blow to the tool 22 in a manner well understood by those skilled in the art.

85 The rear end face of the chuck 20 is provided with a series of clutch or ratchet teeth 24, and the front face of the chuck member or ring 17 is provided with coacting clutch or ratchet teeth 25. These teeth are arranged to interlock, as indicated in Figs. 1 and 6, but the ring 17, as already explained, 90 has a limited longitudinal play, which play is sufficient to permit the teeth 25 to pass over the teeth 24 upon the oscillatory movement of the ring 17 in one direction. The said ring is, however, urged forwardly to secure the inter-engagement of the teeth, by suitable means, in the present embodiment, in the form of plungers 26 that bear against the rear face of the ring 17, being slidably mounted in sockets 27 formed in the front 100 end of the feather ring 11. These plungers are forced outwardly by coiled springs 28 located in the sockets behind them.

Briefly described, the operation of the structure is as follows: Upon the reciprocation of the piston, said piston as already explained, will be given an oscillatory movement by the engagement of the feathers 16 in the spiral grooves 15, and the clutch ring 17 will be oscillated with the piston. During 110

the movement of the piston in one direction, the ring 17 will move in a direction to cause its teeth 25 to ride over the teeth 24, the plungers 26 being forced rearwardly into their sockets 27. When, however, the movement of the ring 17 in the opposite direction takes place, then the plungers 26 will force the ring 17 forwardly, causing the teeth 25 to interlock with the teeth 24, and 10 effecting a slight turning movement of the chuck, this movement being, of course, transmitted to the tool 22. The repeated oscillation of the piston and the clutch ring will thus impart a step-by-step rotation to the 15 chuck.

From the foregoing, it is thought that the construction, operation, and many advantages of the herein described invention will be apparent to those skilled in the art, and 20 it will be understood that various changes in the size, shape, proportion, and minor details of construction, may be resorted to without departing from the spirit or sacrificing 25 any of the advantages of the invention.

Having thus fully described my invention, what I claim as new, and desire to secure by Letters Patent, is:—

1. In a motor, the combination with a cylinder member and a piston having a back and forth movement therein, of means for causing an oscillatory movement of the piston, a rotatable chuck, and means actuated by the piston on its oscillatory movement for effecting a rotary movement of the chuck. 30
35 2. In a motor, the combination with a cylinder member and a reciprocatory piston operating therein, of means fixed with relation to the cylinder member to effect an oscillation of the piston on its reciprocation, a rotary chuck, and means actuated by the piston on its oscillatory movement for effecting a step-by-step rotary movement of the chuck.

3. In a motor, the combination with a cylinder member and a reciprocatory hammer piston operating therein, of means fixed with relation to the cylinder member and having a feathered engagement with the piston to effect an oscillation thereof on its reciprocation, a rotary chuck, and means that oscillates with the piston and operates on the chuck to effect a step-by-step rotary movement thereof.

4. In a motor, the combination with a cylinder member, of a piston therein having a back and forth movement, a rotatable chuck having a rear clutch face, a clutch member having a front clutch face coacting with the rear clutch face of the chuck and also having a feathered engagement with the piston, a fixed member having a feathered engagement with the piston, and spring means interposed between the fixed member and clutch member for urging the latter forwardly.

5. In a motor, the combination with a cylinder member, of a piston therein having a back and forth movement, a fixed member having a feathered engagement with the piston to determine its path-of movement, a rotatable chuck having a rear clutch face, and a clutch member having a front clutch face coacting with the rear clutch face of the chuck and also having a feathered engagement with the piston within the fixed member and alongside said feathered engagement of said fixed member with the piston. 70
75

6. In a motor, the combination with a cylinder member, of a piston therein having a back and forth movement, a fixed member having spaced feathered engagements with the piston to determine its path of movement, a rotatable chuck having a rear clutch face, a clutch member having a front clutch face coacting with the rear clutch face of the chuck and also having rearwardly extending portions that are located within the fixed member between the latter's feathered engagements with the piston, said portions having feathered engagements with the piston, and spring means interposed between the fixed member and the clutch member for urging the latter forwardly. 80
85
90

7. In a motor, the combination with a cylinder member, of an oscillatory piston operating therein, an oscillatory clutch ring surrounding the piston, said ring furthermore having a limited longitudinal play, spring mechanism for urging the ring forwardly, 95 said ring having a ratchet front face, a rotatable chuck having a rear ratchet face that coacts with the front face of the ring, and means for effecting an oscillation of the ring by the piston on the latter's oscillation and thereby effecting a step-by-step rotation of the chuck. 100
105

8. In a motor, the combination with a cylinder member, of a reciprocatory piston operating therein, means for effecting an oscillation of the piston, an oscillatory clutch ring surrounding the piston and feathered thereto so as to oscillate therewith, said clutch ring having a ratchet front face, a rotatable chuck having a rear ratchet face coacting with the front face of the ring, and means for yieldingly urging the ring longitudinally toward the chuck. 110
115

9. In a motor, the combination with a cylinder member, of a reciprocatory piston operating therein, a fixed feather element carried by the cylinder member and slidably engaged by the piston, a clutch ring surrounding a portion of the piston and having a front ratchet face, a rotatable chuck having a rear ratchet face engaged by the front ratchet of the ring, a connection between the piston and ring for effecting an oscillation of the latter, and spring means interposed between the ring and the fixed 120
125
130

feather element for urging the ring forward to maintain the ratchet faces in coacting relation.

10. In a motor, the combination with a cylinder member, of a hammer piston having longitudinal and spiral grooves, a ring fixed to the cylinder and having feathers engaging in the spiral grooves, a clutch ring surrounding the piston and having feathers engaged in the longitudinal grooves, a spring interposed between the two rings, a rotata-

ble chuck, and face ratchet or clutch teeth located on the rear end of the chuck and the front end of the clutch ring, said teeth detachably inter-engaging.

In testimony whereof I have hereunto set my hand in presence of two subscribing witnesses.
